UNITED STATES PATENT OFFICE.

HENRY ROSE, OF FAYETTE, MISSOURI.

STAPLE-SETTING INSTRUMENT.

SPECIFICATION forming part of Letters Patent No. 308,994, dated December 9, 1884.

Application filed September 10, 1884. (No model.)

To all whom it may concern:

Be it known that I, HENRY ROSE, of Fayette, Howard county, Missouri, have invented a new and useful Improvement in Metallic Staple-Fastening Devices, of which the following is a full, clear, and exact description.

This invention consists in a setting implement for use in connection with metallic staples, substantially as hereinafter described, for closing or securing seams in boots and shoes, in bags of leather, cloth, or other material, in pantaloons and overalls, in fastening straps of leather, cloth, paper, or similar or other materials, also in securing rips in seams of boots or shoes, and for other purposes.

Reference is to be had to the accompanying drawings, forming a part of this specification, in which similar letters of reference indicate corresponding parts in all the figures.

Figure 1 represents a partially - sectional side view of the setting implement with a metallic staple in its place therein, also showing two pieces of material in position for being secured by the staple, all in accordance with my invention. Fig. 2 is a transverse section of the same on the line *x x* in Fig. 1; Fig. 3, a top view of the implement, and Fig. 4 a sectional view of two pieces of material as united by the staple.

The setting implement resembles, in its general construction, a pair of tongs or pliers, being composed of two crossing links, A A', pivoted together, as at *b*', and the rear portions of which form handles, while the forward portions are constructed to form jaws *a* *a'*. The under or acting face portion of the upper or one jaw, *a*, has a dovetail groove, *b*, cut in it for the reception and retention of the metallic staple or fastening *B*, which is of tapering construction, with its back that is seated within the groove *b* made to arch inward for the purpose of bringing the pressure when the setting implement is closed more upon the raised ends of the staple than on its center. The groove *b* may extend either entirely or only partially across the face of the jaw *a*. The upper or acting face of the lower or other jaw, *a'*, is recessed to receive and properly direct the lower sharpened points or ends of the staple *B* after said ends have been forced or pressed through the seam or pieces of material C C to be united, and the jaws of the implement are brought together to secure the fastening or close the staple on the

work. This recess in the jaw *a'* may be variously shaped. Thus it may be merely dished or oval, or be in the form of a groove or grooves of any suitable configuration. If grooved, however, then two grooves, *c c*, extending either wholly or partially over the face of said jaw *a'*, leaving a raised central portion between them, should be used, and such grooves be of such dimensions and at such a distance apart that the sharp points or ends of the staple will be properly received within them.

After the implement holding the metallic staple *B* in its jaw *a*, as described, has been properly adjusted to the work, with the seamed portions of the goods, or two pieces, C C, of the material or materials to be united, arranged over the other jaw, *a'*, the implement is manipulated to close the jaws, causing the points of the staple to be projected through the two pieces of material and into the grooves in the jaw *a'*, and so that the continued closing of the jaws will cause the pointed end portions of the staple to be first bent inward or toward each other and afterward upward into the material; thereby securely fastening the goods, as shown in Fig. 4. The recess or grooves in the jaw *a'* are of suitable hollow, rounded, or shelving shape in transverse section, to insure the legs or pointed portions of the staples being thus bent inward and upward by the action of the implement. After the staple has been thus set or closed, and the seam or goods secured, the implement is drawn slightly to one side, which detaches it from the staple. If necessary to secure the pressing of the staple still closer to its place in and on the goods, the setting implement may be closed again on the staple.

Having thus described my invention, I claim as new and desire to secure by Letters Patent—

In a staple-setting instrument, the levers A A', one having a jaw, *a'*, provided with parallel concaved grooves or channels *c*, and the other lever having a jaw, *a*, provided with a holding groove, *b*, of dovetail construction to receive and effect the retention therein of the fastening device or staple, the instrument being withdrawn from the staple laterally after the securing of the latter to the article, substantially as and for the purpose set forth.

HENRY ROSE.
